QUARTZ SEAL AND METHOD OF PRODUC-
ING THE SAME

Ellis O. Erickson, Pasadena, Calif., assignor to
Claude Neon Electrical Products Corporation,
Ltd., Wilmington, Del., a Corporation of Delaware

Original application June 16, 1930, Serial No.
461,351. Divided and this application January
27, 1933. Serial No. 653,766

4 Claims. (Cl. 176—36)

This is a division of my copending application, Serial No. 461,351, filed June 16, 1930, for quartz seal and method of producing the same, in which is claimed the method of producing the seal, 5 while this application is particularly directed to the seal which is formed by my method.

This invention relates to a quartz seal and to a method of producing the same. In various quartz apparatus, it is desired to pass a metallic 10 wire into the vessel and form an air-tight seal around the wire. Thus, in certain vacuum apparatus, neon tubes, etc., electrodes, filaments, or other parts within the tube are desired to be provided with a lead line for making electrical 15 connections. It is necessary that these lead lines be sealed to the quartz with a substantially air-tight seal. Since the coefficient of expansion of quartz is so widely different from any metal which can be utilized as such a lead line conduit, it is extremely difficult to effect a non-leaking seal. Also, because of the fact that the 20 quartz requires such a high temperature, i. e. 1700 to 1750° C. before it can be worked, difficulty is encountered in making a seal without burning the metal. The difficulties of forming 25 the seal are great, and the number of metals suitable for use as a seal are extremely limited.

It is the purpose of the present invention to provide a seal for passing a metal lead line 30 through quartz and a process of producing the same which is satisfactory in practice and simple and economical to use and construct.

Generally considered, the invention comprehends that by providing a very fine diameter 35 wire in a portion of the lead line and over a sufficient length the quartz may be caused to seal sufficiently tight to said wire as to eliminate practically all leakage. The invention also comprehends a construction and process of construction such as a seal which is simple to carry 40 out and which assures against the metal in this fine lead line being vaporized from and broken during operations of forming a seal into the desired finished apparatus.

The invention also provides a seal which is formed independently of, and which is separate 45 from, the apparatus into which it is to be finally sealed, and provides a form of seal which may be readily welded in place in the desired apparatus in a simple manner without danger of destruction of the seal.

The invention also provides a form of seal especially suitable for connecting the electrodes 50 of Geissler tubes, such as neon tubes, when the tube is to be made of quartz. Neon or Geissler

tubes made of quartz are of special value as therapeutic lamps.

The present invention, together with various additional objects and advantages, will best be understood from the description of a preferred form or example of a quartz seal and process 60 of producing the same, embodying the invention. The seal and process are illustrated by reference to the accompanying drawing, in which

Figure 1 is a sectional view of a capillary used 65 in forming a seal.

Figure 2 is an illustration of the lead wire utilized in the seal.

Figure 3 is a seal unit or blank.

Figure 4 is a blank after it is operated upon 70 for attaching an electrode.

Figure 5 illustrates the seal attached to the electrode.

Figure 6 illustrates the position of the seal and electrode in a tube before the operation of 75 combining the seal with the tube so that the seal may function in the apparatus of which the tube is a part.

Figure 7 illustrates the seal after it has been 80 welded to the tube.

Figure 8 illustrates the seal with its outer end removed in order that electrical connections may be made.

Figure 9 is a sectional view of the capillary and lead wire assembled and connected to an 85 evacuating pump.

Referring to the drawing:

In preparing the seal, I prefer to employ a capillary section 2 having one end 3 with a narrow bore closed at its end. The narrow bore, 90 for example, is preferably one millimeter in diameter. The narrow bore portion of the capillary connects with a larger bore section 4 and then with an enlargement 5 which may serve as a nipple for attaching the capillary to the hose 95 of a vacuum pump.

In Figure 2 there is illustrated a wire which is to form a lead to an electrical part and with which the seal is to be made. The wire comprises a central portion 6 of a very fine diameter 100 which, for example, is .0006 inches in diameter. This wire must be made of metal having a melting point higher than that of quartz and preferably of high tensile strength, and tungsten is the metal I have generally chosen as best for 105 filling these requirements and also being one which is commercially available in this small diameter. The length of the section 6 of the lead wire should be sufficient to insure an adequate seal. Generally speaking, the larger the diame- 110

ter, the longer length necessary to insure a seal, while the smaller the diameter the less length. I have found in practice that with a .0006 inch diameter tungsten wire of $\frac{3}{4}$ inch in length a seal of quartz may be produced which fails to register any leakage. To the ends of this section 6 of wire there should be welded lead lines 7 and 8 of a flexible wire and of larger diameter. The material of the leads to the sealing wire 6 10 may be varied, but the requirement for the use of a metal having a melting point higher than that of quartz and also of substantially flexible nature, even after having been subjected to high temperatures at which quartz is worked, has led 15 to the selection of molybdenum. While the diameter of the leads 7 and 8 is not critical, I have, for example, employed molybdenum in .015 inches in diameter.

In the process of making the seal, the wire 20 shown in Figure 2 is placed within the narrow bore of capillary 2 and the capillary 2 is then connected with a hose 9, as shown in Figure 9, leading to a vacuum pump. The capillary is then heated between the lines M—M and N—N 25 in Figure 9 until the quartz is sufficiently soft that under the vacuum it will be collapsed upon the wire. Finally, the section including the wire is fused off forming the unit illustrated in Figure 3.

30 The capsule should hang in a vertical position during the collapsing operation and is preferably clamped in that position by means of a clamp about the rubber tube at a point where the capsule enters it. The heating is preferably by a 35 hand torch and is started preferably about the line N—N and the heating progressed slowly upward to the line M—M as the lower portions of the capsules are collapsed.

By this process the unit shown in Figure 3 40 is produced, in which the wire of Figure 2 has been completely embedded in quartz.

In order to connect the electrode or other 45 electrical elements with the seal, one end of the seal is then fractured at about the line A—A 50 in Figure 3 and removed from the end of the wire by a fracturing pressure, leaving the seal in the form shown in Figure 4. To the seal is then attached the electrode indicated at 10, the particular electrode indicated being a cylindrical electrode and forming a part of a neon tube. The wire from this electrode is attached to the 55 wire of a seal by a crimp joint or by spot welding. This produces the unit illustrated in Figure 5.

Then, as illustrated in Figure 6, when the seal 60 is to be connected into the apparatus in which it is to be used, the seal of Figure 5 with its electrode is placed within a quartz tube so that the outermost joint between the tungsten and molybdenum wires is at about $\frac{1}{8}$ inch from the open end. The quartz tube is then welded to the

60 seal by directing a small pointed flame to the point indicated by the arrow in Figure 6. Since the wire of the seal is entirely surrounded and enclosed by quartz at the region that this welding operation is performed, the high temperature of the welding operation is unable to vaporize the metal of the wire and accordingly the seal is preserved and the wire preserved continues so that it is capable of acting as a conductor.

65 This operation produces a seal as shown in Figure 7. This seal is then marked along the line B—B and fractured and the excess removed by crushing, leaving the finished seal as shown in Figure 8. In the finished seal one end of molybdenum wire protrudes as illustrated, and 90 can be utilized for making electrical connections. Molybdenum does not solder readily, but a hook can be made in the end of the wire and embedded in a drop of solder in the end of the metal cap. An optional method of connection is to spot weld 95 a connection of Dumet wire and then to solder to the Dumet.

While the process of making a seal herein 100 illustrated and the seal are well adapted to carry out the objects of this invention, various modifications and changes may be made without departing from the principles and objects of the invention, and this invention includes all such changes and modifications as come within the 105 scope of the appended claims.

105 I claim:

1. A seal between a quartz envelope and an electrical lead wire comprising, a relatively fine wire of substantial length having larger wire leads connected to each end thereof, and a 110 quartz covering completely enclosing said fine wire and a portion of each of said larger wire leads.

2. An electrical quartz seal comprising, a substantial length of relatively fine wire having a 115 larger wire attached to each end thereof, and at least partially enclosed within a quartz covering in sealing engagement with the wire assembly.

3. An article of manufacture, comprising a substantial length of relatively fine wire having a larger wire connected to each end thereof, and having a quartz covering surrounding and fused into intimate contact with the entire 125 length of said fine wire and a portion of the length of each of said larger wires.

4. A seal between a quartz envelope and an electrical lead-in wire comprising a substantial length of relatively fine wire having a melting 130 point higher than quartz, a larger diameter wire having a higher melting point than quartz secured to each end of said fine wire, and a covering of quartz fused into intimate contact with and completely surrounding the fine wire and a 135 portion of each of said larger wires.

ELLIS O. ERICKSON.
